UNITED STATES PATENT OFFICE.

PERRY J. BRADISH, OF KANSAS CITY, MISSOURI.

DESIGN FOR A DOORSTOP.

Application filed August 28, 1925. Serial No. 14,627. Term of patent 7 years.

To all whom it may concern:

Be it known that I, PERRY J. BRADISH, a citizen of the United States, residing at Kansas City, in the county of Jackson and State of Missouri, have invented a new, original, and ornamental Design for Doorstop, of which the following is a specification, reference being had to the accompanying drawing, forming a part thereof.

I claim:

The ornamental design for a doorstop as shown.

PERRY J. BRADISH.
